PLUG VALVE

Robert Bischoff, Baltimore, Md.

Application October 3, 1940, Serial No. 359,464

8 Claims. (Cl. 74—22)

The invention relates to improvements in operating gear for rotary plug valves of the tapered or frustoconical type or other type of rotary valve in which it is helpful to move these valves in the direction of its axis, thus contributing to the facility with which the valve is operated in opening and closing. In the large sizes of valves the friction due to hydraulic pressure and other causes becomes so great that it offers almost insurmountable resistance to opening the valve and one feature of the invention provides an automatic device for slightly raising or moving the valve in the direction of the axis prior to opening so as to lift the frustoconical valve member or plug from its corresponding frustoconical seat, the movement being slight, thereafter the operating force which has served to lift the plug is automatically changed in its application so that the valve is opened by the same operating force or tendency applied in the same direction without attention on the part of the operator or necessity for knowledge of the fact that opening is a two step operation consisting of first lifting and then turning in rotation through a limited arc.

It is further of interest that the plug having been first lifted from its seat and then rotated to open position is in accordance with the functioning of the operating mechanism in its most complete and highly developed form again lowered to its seat in open position. This reseating of the plug prevents fouling of the contacting surfaces of the seat and plug and the accumulation of impurities thereon.

The lowering or reseating step is automatic as are the first two steps of the operation in that the motion of the control lever or other manual or power operating device is not varied for this purpose from the motion of the operating lever of a simple plug valve which is not raised or lowered in opening or closing.

The valve operating device, in the form shown, comprises lifting means as a screw thread or the like on the valve stem and a follower or cooperating nut to which the operating force is applied by means of a lever or equivalent means as a connection from a power motor. In opening the valve the nut or corresponding element raises the plug. When the desired lifting effect has been accomplished, the nut becomes fixed relatively to the plug and stem and the operating force is applied directly to the opening or turning of the plug on its axis. At the full open position the plug may be lowered to its seat and in closing the motion described is reversed and the plug is

finally forced down on its seat by the action of the thread.

The features and details of the operating mechanism will be more fully described in connection with the drawings.

Throughout the discussion the valve axis is assumed to be upright, the word raising being used to indicate a motion away from the seat in the direction of the valve or plug axis.

10 In operating large plug valves in controlling liquids under considerable pressure, it is noted that there is, following the initial cracking of the valve in opening, an excess resistance to opening. This may be explained as due to the 15 impingement of a jet of liquid thus released against the wall of the passage or opening in the plug, tending to rotate the same in the direction of closing.

20 A further improvement forming part of the invention provides means for overcoming this resistance. This improved feature is embodied in a plug valve, the plug being hollow in that it has a central hollow extending in the direction of the axis and a stationary core in said

25 opening, the core being integral with the valve casing or affixed thereto for this purpose. The plug is thus in the form of a frustoconical sleeve rotatively mounted between the core and the frustoconical seat. The sleeve valve member has 30 lateral openings to register with the usual seat openings in the open position of the valve and the core has a passage aligned with the said seat openings so that the openings on that the sleeve valve member register with both the seat openings and the core passage in the open position of the valve.

35 By providing this stationary core with its passage permanently aligned with the seat opening any impact forces of a lateral jet or other forces resulting from the initial opening are taken up by the stationary core and transmitted to the casing without in any way interfering with the opening motion of the valve.

40 In the accompanying drawings, I have illustrated a valve embodying the features of my invention in the preferred form.

In the drawings:

Fig. 1 is a top plan view of the valve casing with the operating mechanism exposed and in the relation corresponding to the closed position of the valve, the cover being removed.

Fig. 2 is a bottom plan view of the cover, portions being broken away for convenience of illustration.

Fig. 3 is an elevation of the casing which en-

closes the valve and the operating mechanism, the portion of the casing containing the latter being broken away and shown in section on the line 3—3 of Fig. 1.

Fig. 4 is a fragmentary view looking at the cam path and cam follower as from the left in Fig. 3, the view being in section on the line 4—4 in Fig. 8, looking to the right.

Fig. 5 is a section on the line 5—5 in Fig. 8 looking downwardly and showing the carrier and its support or abutment and the cavities therein, the latter containing the carrier lugs which enter said cavities in the open position of the valve.

Fig. 6 is a vertical section on the line 6—6 in Fig. 3, taken in a plane at right angles to the plane of Fig. 3, the valve being closed.

Fig. 7 is a top plan view of the valve operating mechanism in the relation corresponding to the open position of the valve.

Fig. 8 is a section on the line 8—8 in Fig. 7.

Fig. 9 is a section corresponding to Fig. 6 showing the valve open and elevated, and is spaced in an axial direction from its seat in which position it is ready to be lowered.

Fig. 10 is a central horizontal section through a modified sleeve type of valve the same being shown in closed position.

Fig. 11 is a vertical axial section through the same on line 11—11, Fig. 10, the valve being in closed position.

Fig. 12 is a similar section showing the valve open.

Fig. 13 is a one-half axial section through the axis of the valve in open position the same being taken in a plane at right angles to Fig. 12.

Fig. 14 is a perspective detail view of the core of the sleeve type valve.

In the operation of the valve, all motions are either rotative about the axis or motions of transition of the plug and stem in the direction of the axis, the valve being assumed for the purpose of description to be positioned with its axis vertical. The terms raising or lifting of the plug being used to, without reference to its actual position, indicate the spacing or movement of the plug in the direction of the axis and away from the seat, whereby a clearance is established between the plug and the seat and the terms lowering, dropping or depressing of the plug is used to indicate a motion of the plug in the direction of the axis and toward the seat, whereby the valve clearance may be closed and the frustoconical surface of the plug is brought in contact with the seat. To avoid reference in the claims to the valve and the motions of the valve in defining the valve gear, the closed position of the valve or any corresponding initial position is referred to as the rearmost position from which the valve and stem are turned forwardly in opening or otherwise operating the valve from closed position, an open position or a position of the gear corresponding to an open position of the valve being referred to as the forward position of the gear, it being understood that various types of valve which are turned or rotated from open to closed position and vice versa in which lifting from the seat is beneficial may be operated by this valve gear. It is conceivable that the gear may be modified to suit valves having more than one open or closed position.

The plug or valve member may be provided with a sealing surface (not shown) similar in form, as the seat or seats of the valve casing.

Referring to the drawings by numerals, each of which is used to indicate the same or similar parts in the different figures, the construction shown comprises a frustoconical plug or valve member 1, having a valve stem 2, which is coaxial with the plug, extending upwardly above the same and for a slight distance below the plug at 2' into a bearing 3 in the valve casing 4. This casing has a frustoconical seat 5 for the frustoconical plug or valve member 1, the closed position of the plug in its seat and the shape of the plug and seat and the location of the port being substantially in accordance with the usual practice.

15 The valve casing 4 has a cover 4' secured by bolts and this casing is provided with upwardly extending struts 6 on which is rigidly supported the casing 7 for the valve operating mechanism. This casing 7 has a cover 8 secured by cap screws or bolts 9. The valve stem 2 extends upwardly from the valve casing 4 through a packing box and gland 10 into the upper or operating mechanism casing 7, the two casings being in axial alignment as shown in Figs. 1 and 3. If so desired, the lower portion of the packing box in cover 4' may be arranged as to provide for a bearing similar to bearing 3.

20 The upper end of the valve stem 2 is threaded at 12 or otherwise provided with similar or equivalent lifting mechanism at its upper end and this thread 12 is shown as a multiple thread and in the form of the invention illustrated is a left handed thread which provides for lifting by counterclockwise motion of the valve lever as hereinafter described.

25 Co-operating with and engaging the thread 12 is a lifting and operating nut 14 which may be provided with an angular head 15 for engagement by a valve lever having a corresponding socket, it being understood that the valve may be hand operated or operated by means of a steam cylinder or other power in accordance with the conditions of the installation.

30 The nut 14 below the angular head 15 is cylindrical and extends through a suitable hole or bearing 16 in the cover 8 of the casing 7, being provided inside the casing and beneath the cover with a flange 17 which is secured by means of bolts 18, see Fig. 1, to the carrier 19. In this connection, it should be understood that in assembling the nut 14 is threaded downwardly over the end of the stem and the cover 8 being removed, the top of the nut is entered into the hole or bearing 16 from below and the cover is then brought downwardly to position. The precise details being subject to wide variation.

35 The carrier 19, just referred to, is preferably of U shaped cross section in a vertical plane as shown in Fig. 3. The nut 14 is secured to the upper arm and the lower arm is provided with an opening 20 through which the stem 2 extends. On each side of this opening the carrier is provided with depending supporting lugs 21 which, in the lowermost open position of the plug, enter the lug cavities 22 in the floor 7' of casing 7 permitting the carrier to move downwardly to seat the plug in open position as described. The cavities 22 are of considerably greater extent in the direction of a circumference about the valve axis than are lugs 21. These lugs 21 in all other positions of the carrier 19 rest on or near the bottom wall or floor 7' of the casing 7 supporting the carrier at the level shown in Fig. 3 in all positions except the open position of the valve, the weight of the carrier being at times carried

by follower rollers 24' and 25'. The floor of the casing may be referred to as a support or bottom abutment for the carrier, the bottom surface 8' of the top cover 8 being the axially opposite or top abutment.

The carrier 19 may be further provided with radial arms and hubs 24 and 25 on the ends of which are mounted the cam rollers 24' and 25' respectively. These rollers engage supporting cam tracks 26 and 27 on the inside of the casing 7 and may be double and adapted to engage the rollers from above and below, i. e., see Figs. 1 and 3. The upper cam tracks serve to force the plug down on its seat.

The upper and lower U arms 28 of the carrier 19 are slotted at 29, or otherwise adapted for variable connection to the valve stem 2 as hereinafter described. In the form shown, the slots in the two arms are of the same form and location one directly over the other being substantially parallel to each other, the shape and location of the slots being subject to some variation. The slot, though not exactly radial, is shown as of radial tendency and in the closed position as shown it is substantially at right angles to the cooperating slot 30 formed in the operating arm 31 which latter is rigidly secured to the valve stem in any suitable manner as by means of set screw 32. This arm is between the carrier arms.

The carrier and arm slots and hence the carrier 19 and the operating arm 31 in which the slots are formed and hence the nut 14 and the valve plug 1 are connected by an upright control pin 33 shown in top plan in Fig. 1 and in side elevation in Fig. 3. This pin is, in turn, mounted to ride in and is guided by guide and control slots 34 and 34' in the floor 7' and in the bottom surface of the cover 8. The respective slots 34 and 34' being of the same pattern, i. e., parallel and in direct registration in a vertical direction which means in a direction parallel to the valve axis. The slots 34 and 34' are circumferential for the extent of the opening and closing arc of the plug and at the end marked A there is a portion which exactly corresponds to slot 30 in the arm 31 in the closed position of the valve. Slot 30 in arm 31 and corresponding portion A' of slots 34 and 34' are shown substantially straight. If so desired, all or any part of these slots may be slightly curved, for purposes of providing means for causing the plug to rotate during the initial lifting of the plug in opening thereby introducing a spiral motion to the plug.

As already pointed out, the valve plug 1 when closed fits in its seat 5 in substantial accordance to the usual practice in connection with frustoconical plug valves and as shown the casing 4 is provided with inlet and outlet passages or ports 40, and the plug or valve 1 has central passage 42 which registers at its ends with the ports 40 in the final open position of the valve.

In the preferred form of the valve, there is a finished seating surface 5', Fig. 6, surrounding each port 40, but the plug surface is shown finished in the form of a continuous arcuate frustoconical surface.

The functioning of the valve operating mechanism will now be explained, starting from the closed position of the valve as shown in Figs. 1 and 3. To operate the valve for purposes of illustration and under ordinary circumstances when the valve is to be hand operated, a handle not shown, may be used, the same being in the form of a plain socket wrench having a cavity to fit the angular head 15.

To conform to established engineering practice, the valve is designed to open with a left handed, or counterclockwise motion, and to this end the threads on the valve stem and actuating nut 14 are of a left handed phase.

In opening the valve the nut 14 is rotated counterclockwise and the arm 31 being secured to the valve stem, and the nut 14 being secured to carrier 19, and the pin 33 which connects the arm, plug 1 and the carrier, and hence the nut 14, by its engagement with slots 29 and 30 traveling in the guideways 34 and 34' moves with the rotation of the nut 14 outwardly from its initial position shown in Fig. 1 to the point A of said guideways 34 and 34'. The arm 31 thus remaining stationary while carrier 19 turns through a small arc. The nut 14 is thus caused to rotate relatively to the stem 2 which being integral with the plug 1 is stationary, i. e., the arm 28 of the carrier with its slots 29 containing pin 33, moving outwardly in Fig. 1 until the said pin reaches the point A as aforesaid. During this time the arm 31, as aforesaid, is stationary and the stem 2 has not rotated, but the nut 14 having turned with the carrier 19 relatively to the stem, raises the latter and the valve or plug in conformance to the pitch of the thread 12, it being noted that the nut 14 is supported by the carrier 19 which bears by way of lugs 21 on the floor 7' of the casing 1.

By further motion of the nut 14 rotated by any suitable means the pin 33 now moves in counterclockwise rotation but to the right in Fig. 1 along the circumferential portion B of the guide slots 34 and 34', the carrier 19, nut 14, arm 31, plug 1, and stem 2 and the rollers 24' and 25' rotating together about the valve axis. In the course of this rotation the rollers 24' and 25' arrive on and become supported by the cam tracks 26 and 27.

The pressure on the lugs 21 which rest on the floor at 7' of the casing 7 is thus somewhat relieved and as the plug and stem etc., continue to rotate with the nut 14, the carrier 19 and the arm 31 moving together, the lugs 21 enter the cavities 22 in the casing floor 7' or rather comes over the same and the rollers 24' and 25' pass down to the low part of the cams 26, 27 at C. When the pin 33 reaches the end of the slot 34 at D, the plug reaches its full open position and at the same time drops into its seat in close contact therewith thus preventing the passage of the liquid between the finished frustoconical surface of the plug and the seating surface 5' of the valve casing which would cause fouling of the seat. The dropping of the lugs 21 into their respective cavities 22 may also act as stopping means to hold the valve openings and ports in alignment.

Having reference to Fig. 4, the lugs 21 are so placed as to enter cavities 22 in full open position of the valve. The valve may be slightly raised when the rollers 24' and 25' encounter the incline of the cams at C', and the incline C eases the valve downwardly preventing the bumping of the valve as lugs 21 pass into the cavities 22.

In closing, which is the next operation to be described, the plug is moved in clockwise rotation by the nut engaged by a socket wrench handle or other means previously discussed. As will be noticed from Fig. 5, which shows the lugs in the closed position of the valve, the cavities 22 are of slightly greater extent in the direction of a circumference about the valve axis than are the lugs

21 which permits the plug, the nut and carrier and arm, as aforesaid, to be moved in right handed rotation as a unit. During this movement the rollers 24' and 25' move up the incline C of the respective cam tracks 26 and 27, the lugs 21 being thus raised out of the cavities 22 and the carrier 19 which was dropped at the end of the closing operation is thus raised.

By right handed operation, i. e., clockwise swinging of the operating lever, the pin 33 having, at the end of the opening motion or operation, reached the end of cam slot 34 indicated by D at the right, said pin in the closing operation now moves to the left along said slot to the position A, the arm 31, carrier 19, nut 14, and the valve stem moving together, it being understood that the plug during this entire closing motion after the rollers 24' and 25' pass up the incline, is elevated so that it clears the seat and moves without friction. It may be noted here that the stem 2 was taken up by nut 14 in the initial opening motion and does not change its relation to the nut and carrier until the step of forcing the plug down on its seat in closed position is about to take place, as now to be described.

When the parts move to the position stated in which the pin 33 occupies the position A, the plug is at the closed angle but raised above its seat; and with continued rotation of the nut 14 in clockwise direction the arm 31 now being stationary on account of the coincidence of slots 30, 34 and 34' from A to A', the nut and carrier rotate relatively to the arm 31 and stem 2 in a right handed direction whereby the thread being left handed, the stem is moved downwardly through the nut and the plug is forced down against its seat. The nut flange 17 treated as part of the carrier reacts against the bottom surface 8' of the cover 8 of the casing which acts as an upper abutment. It will be understood that at this time the followers 24', 25' having long since left the cams 26 and 27 and the lugs 21 having been raised from cavities 22 have rested on and moved along the floor 7' of the casing 7. The parts are then returned to the position shown in Figs. 1 and 3.

An important accomplishment of the invention, as illustrated in Figs. 1 to 9, resides in the practically frictionless opening and closing of large valves controlling high pressures and particularly in the combination in automatic relation of the lifting and opening operation and the return of the plug to its seat in open position without variation of the normal actuating motion of the lever or other equivalent means employed. The raising of the plug from full open position by the rotation of the valve by the lever in closing direction and the mechanism whereby it is returned to closed position and the means and manner of forcing the plug down against its seat, both said lifting and closing and downward forcing motion being accomplished by a single closing motion of the lever are regarded as of importance.

It is also notable that the parts essential to these automatically related operations are comparatively simple and capable of cheap production and they further are of a nature which would cause them to resist failure and thus reduce cost of maintenance far below the standard which has been regarded as essential to such apparatus as has been previously devised for this purpose. Figs. 10, 11, 12, 13 and 14 show an improved form of plug valve adapted for use with the regular type of operating mechanism or with the improved lifting type of operating mechanism just described. This improved plug valve has a cas-

ing 58 with a frustoconical seat 51 and opposite aligned ports or passages 52, 52' leading through the casing to valve seat 51.

As already pointed out, it has been demonstrated and is a well known fact that in the initial opening of plug valves, particularly the plug valves of large size operated under heavy hydraulic pressures excess resistance is encountered. This resistance is understood to be due to a jet 10 of liquid from the initial opening of the valve impinging on the inclined opposite side of the deflected passage or hole in the plug. The jet is directed at an angle to the normal flow through the valve and thus caused to strike the adjacent 15 end of the wall of the plug opening or passage tending to close the valve or resist opening.

This difficulty has been overcome in the new form of valve by the provision of a central stationary core, the plug proper being in the form 20 of a sleeve. This stationary core, as hereinafter pointed out, has a passage in full alignment with the ports in the seat so that in opening the impingement of the initial jet strikes the wall of the passage in the rigidly supported stationary 25 core and has no appreciable effect in the way of resistance opposed to the opening of the valve.

The stationary core referred to is indicated by reference character 53, being, in the form of the invention shown, of substantially cylindrical outline with the axis of the cylinder coinciding with the valve axis, this core is provided with a central valve passage or port 54 in precise alignment with the ports 52 and 52'. In the form shown, it is secured to the base of the valve casing in any suitable manner as by pins 55 and screw 56. The cylindrical form of the core not only facilitates turning of the valve proper relatively to the core, as hereinafter described, by fitting in a similar opening therein but makes it possible to insert 40 the valve member or sleeve valve 57 from above whereby it enters between the seat and the outer wall of the stationary core 53.

The valve member 57 which may be referred to as a sleeve plug valve is shown in the form of an externally frustoconical sleeve or hollow plug having a cylindrical opening 58 finished to fit the outer surface of the core 53 and to permit turning of the sleeve relatively to the core.

The valve or sleeve plug 57 is shown as provided with ports 59 which are aligned and normally adapted to register with the seat ports 52 and 52' in the open position of the valve and likewise to register with the ends of the core passage 54, the core and passage, as already pointed out, being stationary. The arrangement of the ports may be varied to suit the practice or installation, the elimination of resistance to opening as herein outlined being the main object of the invention.

In the form of the invention shown, the core 53 is somewhat shorter than the plug and its top flat surface 60 is below the upper arc 61 of the ports 52 and 52'. The passage 54 through the core being open at the top into the sleeve plug 57, as indicated, is, therefore, less than full cylindrical but is regarded as sufficient to avoid the harmful closing tendency already described and it has the advantage that the arrangement provides for top wall 62 in the sleeve plug and the connection thereto of the valve stem 63.

Figs. 11 and 12 show the casing support or struts 6 extending to the upper operating casing 7.

The operation and advantages of the new type of valve and valve operating mechanism and the construction thereof having been fully described, 75 I would have it understood that the specific terms

herein are used descriptively rather than in a limiting sense, the scope of the invention being defined in the claims.

What I claim as new and desire to secure by Letters Patent is:

1. An operating mechanism for a valve of the rotary type having a casing and a stem, said operating mechanism comprising a nut threaded on the stem, a carrier secured to the nut, abutment means limiting the play of the nut in axial directions, whereby the nut is enabled to move the stem in an axial direction as it is rotated relatively thereto, an operating arm connected to the stem to turn the same, means connecting the carrier to the arm, said connection having a control, the connection and control comprising means causing the arm and carrier and stem to move in correspondence with the nut, turning together forwardly and backwardly about the axis of the stem through a predetermined arc, said means including a provision for permitting forward turning of the nut prior to the forward turning of the arm and stem, and means for lowering the carrier and nut at the end of said forward turning motion of the stem, whereby the stem is raised at the beginning of said forward motion and lowered at the end of said motion.

2. An operating mechanism for a rotary valve having a casing and a stem, said operating mechanism comprising a nut threaded on the stem, a carrier secured to the nut, abutment means limiting the play of the carrier in axial directions, an operating arm connected to the stem to turn the same, means connecting the carrier to the arm, said connection having a control in the form of co-operating guides, said connection and control comprising means causing the arm and carrier and hence the stem to turn in correspondence with the nut about the axis of the stem, moving together forwardly and backwardly through a predetermined arc but including a provision for permitting turning of the nut prior to the turning of the arm to raise the stem prior to the forward turning motion of the stem and to lower the stem at the end of the arcuate motion of the stem in the backward direction and means for lowering the carrier and hence the stem at the end of the forward turning motion and means for raising said carrier and thereby raising the stem at the beginning of the backward turning motion.

3. An operating mechanism for a rotary valve having a casing and a stem, said operating mechanism comprising a nut threaded on the stem, a carrier secured to the nut, abutment means limiting the play of the carrier in axial directions, an operating arm connected to the stem to turn the same, means connecting the carrier to the arm, said latter connections having controlling means, said connections and control including means causing the carrier and stem to move in correspondence with the nut to turn about the axis of the stem moving together forwardly and backwardly through an arc, said means including a provision for permitting turning of the carrier and nut prior to the turning of the arm and stem in the forward turning motion and at the end of the turning motion of the stem in the backward turning through said arc, means for lowering the carrier, the nut, and the stem near the end of the forward turning motion and means for raising said carrier, nut and stem at the beginning of the backward turning motion, the said turning of the carrier and the nut relatively to the arm prior to the forward rotation serving

10 to raise the stem relatively to the carrier, and the opposite turning of the same relative to the stem at the end of the backward turning motion serving to lower the stem to initial position, the lowering of the carrier and nut and stem at the end of the forward turning serving to bring the stem to its initial level and the raising of the carrier and nut at the beginning of the backward turning motion serving to return the carrier and nut to their initial elevation.

15 4. An operating mechanism for a rotary valve having a casing and a stem, said operating mechanism comprising a nut having a threaded engagement with the stem, a carrier connected to the nut to turn therewith, an actuating arm operatively connected to said stem for turning said stem forwardly and backwardly through a predetermined arc said arm and said carrier having slots which cross in the backward position of the arm and the corresponding position of the stem, a travelling control pin extending through said slots in approximate parallelism with said stem, said casing having a guiding slot in a stationary portion of the casing also engaged by the pin, said guiding slot having a portion which in the closed position of the valve extends outwardly in substantial parallelism and in registration with the slot in said actuating arm, said guiding slot also having a circumferential portion extending from said parallel portion of said guiding slot and in said forward direction therefrom, through an arc corresponding to the length of said predetermined arc, said pin maintaining different portions of said slots in registration in the different positions of the operating mechanism and stem.

20 5. An operating mechanism for a rotary valve having a casing and a stem, said operating mechanism comprising a nut threaded on said stem, a carrier operatively connected to the nut to turn the same, an actuating arm operatively connected to the stem to rotate the stem forwardly and backwardly through an arc, said arm and said carrier having slots which cross in the rearmost position of the parts, a control pin extending approximately in the direction of the axis of the stem through said slots, the casing having a guiding slot in a stationary portion thereof, said latter slot also being engaged by the pin, said guiding slot having a portion which extends outwardly and in registration with the slot in said actuating arm in the rearmost position of the parts, said guiding slot having a circumferential portion extending from said slot outwardly, means providing for the lowering of the carrier and stem as the parts approach the forward position and follower means on the carrier and means on the casing co-operating therewith to raise the carrier as it is rotated from forward to rearmost position.

25 6. An operating mechanism for a rotary valve having a casing and a threaded stem, said operating mechanism comprising a carrier mounted to rotate forwardly and backwardly through a predetermined arc, a nut engaging the thread and secured to said carrier to rotate therewith, an arm connected to the stem to turn the same, means supporting the carrier in axial directions, means connecting said arm to said carrier and control means for said connection providing for the rotation through a small arc of the nut relatively to the arm and stem prior to forward rotation of the stem whereby the stem is lifted causing the same to be supported on said carrier. said

control means including means for thereafter closely limiting the motion of said carrier relatively to the arm and stem whereby the stem is turned with the carrier and nut through a predetermined arc, a support for the carrier having means permitting downward motion of the carrier at the end of said forward turning motion, and other means for raising the carrier and stem in the initial portion of the backward motion, said connecting permitting rotation of the carrier and nut relatively to the arm and stem at the end of the backward motion to initial position, said rotation being the reverse of the initial rotation of the nut relatively to the stem and serving to move the stem downwardly relatively to the carrier and casing said supporting means for the carrier comprising an upper abutment against which the nut reacts for this purpose.

7. An operating mechanism for a rotary valve having a casing and stem the same comprising an operating nut having a threaded engagement with the stem, a carrier connected to the nut to turn therewith forwardly and backwardly through a predetermined arc, an arm connected to the stem to turn the same and having control means whereby it is connected to the carrier to operate

in correspondence with the carrier providing for initial turning of the nut relatively to the stem to lift the stem at the beginning of the forward turning and to lower it at the end of the backward turning motion, means for lowering the stem and nut and carrier at the end of the forward turning motion and means for raising the stem and nut and carrier at the beginning of the backward turning motion.

8. An operating mechanism for a rotary valve having a casing and stem, the same comprising an actuating member having means for lifting and lowering the stem, a carrier connected to said member to turn therewith forwardly and backwardly through a predetermined arc, an arm connected to the stem to turn the same and having control means whereby it is connected to the carrier to turn in correspondence with the carrier and to said member to lift the stem at the beginning of the forward turning motion and to lower it at the end of the backward turning motion, and means for lowering the carrier and stem at the end of the forward turning motion and for raising the carrier and stem at the beginning of the backward turning motion.

ROBERT BISCHOFF.
